Felix Kivi

By his Atty's, Conrad Schmid

UNITED STATES PATENT OFFICE.

FELIX KIVI, OF SAN FRANCISCO, CALIFORNIA.

SHIRT.

SPECIFICATION forming part of Letters Patent No. 249,186, dated November 8, 1881.

Application filed March 17, 1881. (No model.)

To all whom it may concern:

Be it known that I, FELIX KIVI, of the city and county of San Francisco, in the State of California, have invented certain new and useful Improvements in Shirts; and I do hereby declare that the following is a full, clear, and exact description thereof, reference being had to the accompanying drawings.

My invention relates to certain improvements in the manufacture of shirts; and it consists, first, in making them open in front in a line extending diagonally from the shoulder on one side down along the side edge and across the line of the bosom, and also making the opposite edge diagonal in an opposite direction from the lower end of the bosom to the lower end of the shirt, so that the two edges diverge below the bosom and form an inverted-V-shaped opening; secondly, in extending the side seams 20 entirely down to the lower edge of the shirt and cutting out an inverted-V-shaped opening in the back of the shirt directly opposite the front opening, all as hereinafter more fully described.

Referring to the accompanying drawings, Figure 1 is a front view of my improved shirt, showing the position of the parts when closed. Fig. 2 shows the same when opened.

Let A represent a shirt that is made to open in front. The bosom B is made gradually narrower toward its lower end. One side of the bosom forms the overlapping edge of the opening, and this edge I extend downward below the bosom in a diagonal direction to the bottom 35 of the shirt so that it passes across the line of the bosom. The opposite or underlying edge extends from the middle of the neck downward to near the lower end of the bosom, and thence it extends diagonally downward in an opposite 40 direction from the upper or opposite edge to the lower edge of the shirt.

The shirt is put on by the wearer like a coat,

and the bosom is then folded across the breast and its edge secured to the opposite side by means of buttons. The underlying flap is fastened to the bosom at the middle of the neck-opening by the collar-button passing through a button-hole in each. The two edges below the bosom will then diverge in opposite directions, leaving an inverted-V-shaped opening, 50 C, in front below the bosom.

The side seams I sew up their entire length. I then cut out an inverted-V-shaped piece from the tail of the shirt in the back, directly opposite the front opening, so that the two sides of 55 the shirt will part in opposite directions. By this arrangement the shirt is rendered much more comfortable for the wearer, as each side can be tucked down into the leg of the pantaloons leaving a smooth part in front and thus 60 avoid the bunching of material in the front part of the pants above the crotch.

A shirt constructed in this way is also much more easily done up, as it can be spread out to be ironed without drawing it on an ironing-board.

Having thus described my invention, what I claim, and desire to secure by Letters Patent, is—

The open-front shirt A, having its front sides 70 adapted to be folded upon and across each other, and fastened by suitable buttons, the edges of the front sides being cut in divergent lines in opposite directions, and having its rear portion directly opposite formed with a V-shaped opening, substantially as and for the purpose set forth.

In witness whereof I have hereunto set my hand and seal.

FELIX KIVI. [L. S.]

Attest:

W. F. CLARK,
W. VOIT.
